Primary Examiner — Dana K Weiland*Assistant Examiner* — Emily Anna Saunders(74) *Attorney, Agent, or Firm* — Jones Walker LLP(57) **CLAIM**

We claim the ornamental design for a game board, as shown and described.

DESCRIPTION

FIG. 1 is a top plan view of a game board showing our new design; and,

FIG. 2 is a front view thereof.

The broken lines in the drawings illustrate portions of the game board that form no part of the claimed design.

The rear view, the right side view, and the left side view of the game board shown in FIGS. 1-2 are each identical to the front view shown in FIG. 2.

The bottom view of the game board shown in FIGS. 1-2 is flat and has no surface ornamentation.
